UNITED STATES PATENT OFFICE.

JANET G. WALKER, OF LIVERPOOL, ENGLAND.

DESIGN FOR A TRAY OR HOLDER FOR SOAP.

SPECIFICATION forming part of Design No. 35,724, dated February 11, 1902.

Application filed December 5, 1901. Serial No. 84,840. Term of patent 7 years.

To all whom it may concern:

Be it known that I, JANET GERTRUDE WALKER, a citizen of the United States of America, residing at Wavertree, Liverpool, in the county of Lancaster, England, have invented and produced a new and original Design for a Tray or Holder for Soap, which can be hooked onto the rim of a bucket, washtub, or other receptacle, of which the following is a specification, reference being had to the accompanying drawings, forming part thereof.

Figure 1 is a general view of the holder or tray; Fig. 2, an end view.

The holder or tray is of wirework, and comprises the ring-like marginal frame *a*, the upright hook *b*, connected with the frame *a* at one side thereof, and the cross-bars *c*, extend-

ing across the frame *a* and connected therewith at their respective ends. The bars *c*, which form the bottom of the holder, are curved, as shown, so as to impart a concave contour to the grid-like bottom.

I claim—

The design for soap tray or holder substantially as described and shown in the accompanying drawings.

In witness whereof I have hereunto signed my name, this 21st day of November, 1901, in the presence of two subscribing witnesses.

JANET G. WALKER.
